DESIGN FOR A COMBINED BOOK END AND PICTURE FRAME

John F. McGonigal, Philadelphia, Pa.

Application December 3, 1943, Serial No. 111,891

Term of patent 14 years

(Cl. D33—1)

To all whom it may concern:

Be it known that I, John F. McGonigal, a citizen of the United States, residing at Philadelphia, in the county of Philadelphia and State of Pennsylvania, have invented a new, original, and ornamental Design for a Combined Book End and Picture Frame, of which the following is a specification, reference being had to the accompanying drawing, forming part thereof, in which the single figure is a perspective view of a com-

bined book end and picture frame, showing my new design.

The rear face of the article is a plain flat surface.

I claim:

The ornamental design for a combined book end and picture frame, substantially as shown and described.

JOHN F. McGONIGAL.
